UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF NEW YORK, N. Y., A CORPORATION OF DELAWARE.

INDEX OR FILE.

Application filed June 29, 1925. Serial No. 40,320.

This invention relates to index devices of the class in which a series of index cards or reference members are arranged upon a carrying frame or in a drawer or similar supporting device in such a manner that a portion of each is exposed to view, one above the other, to facilitate ready reference thereto, the exposed portion being adapted to bear information regarding the nature of the data upon the remaining portion of the card.

More particularly, the invention relates to a corner-retaining member designed for application to a reference member or card, and adapted to removably support another card or the like thereon. Such a retaining member may be applied to an index element of an equipment already in use or may be furnished with a new equipment as a part thereof. In either case, the individual index elements of the equipment will be adapted by the addition of such members to detachably retain another card thereon, the margin of which will be exposed to view when the original elements, now having become card holders, are arranged in the over-lapped relation above noted.

Various forms of card holders have been provided contemplating some of the features of the above desirable ones, among which are the forms shown in my co-pending applications No. 690,755, filed February 5, 1924 and No. 24,765, filed April 21, 1925. The form embodying the features of this invention may be considered as an improvement over these preceding applications by having included in its structure, among others, the novel feature of being adapted to positively prevent the possibility of the corners of an overlying card holder engaging the edge of the card-retaining member on the card holder next below. This feature is obtained by substantially enclosing the card holder corners at the free margin thereof, with a suitably formed corner member. It is desired that such a member be of such form that all of the advantages of the preceding forms be retained while at the same time increasing the convenience and efficiency in the use of this type of index. It is also desirable that such a member be of such construction that the corners of the card holders will be protected against mutilation due to constant manipulation, while

at the same time providing a means to retain an additional card or cards thereon. 55

One object of this invention is to generally improve card holders or index elements of the above types so that additional cards may be easily attached thereto and detached therefrom, and when so attached may be 60 readily referred to.

Another object of this invention is to provide a card or reference member holder for use in indexes or files of the above type, which is adapted to retain one or more additional cards thereon upon a surface thereof, which will be inexpensive to manufacture and efficient in use. 65

Another object of this invention is to provide a card retaining means of such a form 70 and construction that the same may be readily applied to an index element to adapt said element to removably retain another reference member or card thereon in such a manner that in some instances the side edges 75 and one marginal edge of both will coincide.

Another object of this invention is to provide as a new article of manufacture, a corner member for an index element used in indexes of this type, which may be readily applied to said element, and when so applied will protect the corner associated therewith against possible mutilation by preventing the possibility of the corner catching or 85 engaging with the corner member of an underlying index element, while serving as a card retainer to hold another reference bearing member upon the index element. 80

Other objects of this invention which are 90 improvements in devices of this character, will appear as the same is hereinafter described and claimed.

In the accompanying drawings:

Fig. 1 illustrates generally a supporting 95 frame having a plurality of over-lapping index elements mounted thereon, embodying the features of this invention;

Fig. 2 is a section on line 2—2 of Fig. 1;

Fig. 3 is an enlarged side view of one of 100 the index elements;

Fig. 4 is an enlarged front plan view of a corner of one of the index elements showing the preferred form of corner member;

Fig. 5 is an enlarged rear plan view of the 105 corner member upon a card;

Fig. 6 is a section on line 6—6 of Fig. 4;

Fig. 7 is a view similar to Fig. 4, but showing a somewhat modified form of corner member;

Fig. 8 is a rear view of a corner member similar to that shown in Fig. 7;

Fig. 9 is a section on line 9—9 of Fig. 7;

Fig. 10 is a section through one of the index elements at the corner thereof on line 10—10 of Fig. 1, the underlying index element not being in section and shown spaced downwardly therefrom for purposes of illustrating a feature of this invention, the dotted portion of this figure being the natural position of the sectioned portion when in use;

Fig. 11 is a view similar to Fig. 4 but showing another modified form of corner member, the development of the same being shown in dotted lines;

Fig. 12 is a rear view of a corner member similar to that shown in Fig. 11;

Fig. 13 is a section on line 13—13 of Fig. 11;

Fig. 14 is a development view of the corner member shown in Fig. 4, as stamped from a sheet of material;

Fig. 15 is a development view of the corner member shown in Fig. 7;

Fig. 16 is a view of the preferred form of corner member after the same has been bent up from the stamping shown in Fig. 14, and before attaching the same to an index element, and

Fig. 17 is a front plan view of a somewhat modified form of index element adapted to detachably retain an additional card thereon, and embodying the features of this invention.

The supporting frame 10 as illustrated in Fig. 1, comprises a base panel 11, which may be the bottom portion of a drawer, the supporting plate of a swinging leaf, or the base member of a tablet or panel. In this instance, a flanged strip 12 is secured to the base 11. The flanged strip 12 is illustrated in order to provide retaining means for the index elements 13, whereby they will be supported and retained upon the frame 10.

The index elements 13 are illustrated as being composed of two portions 14 and 15, hingedly connected together at 16 in any suitable manner, such as by the spaced-apart members 17 formed integral with both portions 14 and 15. The portion 14 of the index element 13 is provided with rearwardly depressed tongues 18 and 19, adapted to engage the margin of an underlying element and to engage beneath the flanges 20 and 21 of the retaining strip 12 for the same purposes and as described in the patent to Irving Fisher No. 1,048,056 dated December 24, 1912.

Although the index element 13 is illustrated as being of two parts 14 and 15 hingedly

connected together, it is obvious that these particular features are not necessarily required but may be dispensed with under desirable circumstances, and that the two members may be made integral or of one piece without the hinged connection. The elements 13 are illustrated as being suspended or down-hanging, but, of course, they might be directed upwardly if such position was desired.

Each of the index elements 13 is provided with a pair of card-retaining and corner-protecting member 22, associated with the corners adjacent the free margin 23 thereof. This member may be formed as shown at 22 in Figs. 1 to 6, inclusive, 10 and 16, from a blank 22^a Fig. 14, which is stamped out of sheet material, preferably thin sheet-metal; as shown at 24 in Figs. 7, 8, and 9, from a blank 24^a Fig. 15; or as shown at 25 in Figs. 11, 12 and 13, from a blank 25^a, shown in dotted lines of Fig. 11. The members 22, 24 and 25 are preferably preformed from their respective blanks 22^a, 24^a and 25^a before being secured upon the index element.

The member 22 is formed from the blank 22^a by bending the material of the blank about a radius on lines 26 and at an angle of substantially 45 degrees to the edge 29 thereof, which causes the arm portions 27 to assume a position shown in Fig. 16, wherein they are spaced from the plate portion 28 and extend beyond and substantially perpendicular to the edge 29. The pointed ends 30 are then bent upwardly at right angles to the arms. The member is then slipped over a corner of the index element 13, which it readily embraces within the pocket formed between the plate 28 and the arms 27, and is properly positioned thereon by the engagement of the adjacent edges of the index element with the handle 26^a. The pointed ends 30 are then caused to pass through the material forming the index element and are bent over the surface thereof toward the edge 29 and preferably pressed downwardly into the material a slight amount below the surface thereof.

The bends 26^a being made about a radius, being at right angles to each other and substantially meeting at 31, causes the under surface of the corner member 22 at the corner thereof to form what will be termed riding edges 32, which are curved from the plane of the plate 28 diagonally rearwardly in respect to the index element 13, to the plane of the arms 27. Due to the edges 33 of the blank 22^a not being parallel with the edge 29, the riding edges diverge from each other, as shown in Fig. 5, and the above-mentioned curve caused by the bends 26^a will be a gradual one of substantially greater radius than the radius of the bend, as shown in Figs. 3, 6 and 10. The riding edges 32, therefore, provide the means which allows

free movement of the corner of the index element over a shoulder, see Fig. 10, such as formed by the edge 29 and prevents an overlying card from catching thereon or being mutilated thereby.

An index or file provided with index elements having the above-described corner members thereon, may have additional cards or sheets added thereto. For this purpose, 10 the plate 28 and the arms 27 are spaced apart sufficiently to allow more than one thickness of material to be placed therebetween. A card 34 is shown mounted upon the index elements 13 by inserting the corners adjacent 15 one of the margins thereof into the corner members 22 beneath the plate 28. The pointed ends 30 of the corner members 22 being bent toward the edge 29 and pressed into the material of the index element, do 20 not interfere with the insertion of the additional card 34 as no abrupt shoulder is presented obstructing this action. When the added cards 34 are of too great a breadth to be properly supported by the corner members 22 acting alone, a tongue or tongues 35 is provided for engaging the opposite margin thereof, the tongue or tongues 35 being usually struck from the material forming the index element in any desired manner. 25

30 The modified form of corner member 24 shown in Figs. 7, 8, 9 and 15, is formed in a somewhat similar manner as the member 22, previously described. The member 24, however, differs from member 22 in that the 35 bends 36 do not substantially meet at the corner but are spaced apart as at 37, Fig. 15, at which point the edges 38 are joined by an arc. After assembly to an index element as above described regarding member 22, this 40 form of corner member is again bent forwardly on line 39, and therefore, presents a riding edge 40, more or less in a straight line, which extends angularly upward from the plane of the arms 27. The use, action 45 and advantages of the member 24 are the same as those of member 22, and the parts thereof not specifically described are generally similar and are, therefore, designated in the drawings by the same reference characters. As will be noted by reference to the 50 dotted lines in Fig. 9, the corners of the retained card 41, however, do not extend into the pocket between the arms 27 and the plate 28 sufficiently to allow the edges and 55 margins thereof to coincide with the corresponding portions of the index element without some alteration. It is, therefore, desirable, if this advantage is required, to trim off the corner of the added card 60 agonally across the same. This same operation may be found desirable when using the preferred form of corner member 22, except that in this case the index element may be trimmed as at 42, Fig. 5, so that the 65 added card 34 will have free access to the

corner of the corner member 22, as shown in dotted lines in Fig. 6.

The modified form of corner member 25, shown in Figs. 11, 12 and 13, is formed from a rectangular shaped blank 25^a of which 70 portions 43 form the arms, and portion 44 the plate. The arms 43 are bent over an arc along the lines 45 which are at an angle of substantially 45 degrees to the edge 46 and at right angles to each other, substantially 75 meeting at a point 47 which is the corner of the corner member 25. In this instance the edges 48 of the arms 43, form riding edges 49 for the corner member. An ear 50 is provided in each arm portion 43, which is 80 adapted to be inserted through the material of the index element 51 and turned over upon the surface thereof toward the bend 45. Due to the edges 48 being substantially 85 parallel and approximately in contact when the corner member 25 is applied to an index element, the riding edge 49 is curved more sharply than the corresponding edge of the preferred form. This is not a disadvantage, however, and this form of corner member, 90 in so far as its operation and use are concerned, is substantially the equivalent of the preferred form although not being quite so easy to apply, as the material-engaging means, the ears 50, are in a more or less 95 inconvenient position and, therefore, not as readily accessible.

The modified form of index element shown in Fig. 17, differs from the preferred form shown in Fig. 1, mainly in that the corners 100 61 and 62 of the added card 60 opposite the corners engaged by the corner members are passed through diagonal slits provided in the material of the index element instead of the margin thereof being engaged by a 105 tongue, such as 35 of the preferred form.

From the above description it may be seen that the invention has provided an index element having all of the advantages contemplated, and that a novel corner member 110 has been provided readily adaptable to the uses desired thereof, and which may be furnished either as a separate article of manufacture for application to already existing index elements, or which may be applied to 115 a series of such index elements before the same are furnished as a complete index equipment.

The corner member in all forms above described provides what may be termed a 120 triangularly shaped corner pocket, having sides disposed at right angles to each other. The pocket is open at the side thereof which is opposite the right angle for the reception of the corner of an index element. After the 125 member is applied to an index element, a card holder is formed having a triangularly shaped pocket at a corner thereof having an opening therein disposed diagonally across the corner of said index element to receive a 130

corner of an additional card or the like. The corner of the added card may be inserted in the pocket formed between the corner member plate portion and the index element either in a perpendicular or horizontal direction, and when received therein will be retained against lateral or longitudinal movement therefrom by the closed sides of the pocket so formed by the radius bends above described. In the preferred form the edges forming the corner of the added card will coincide with the corresponding edges of the index element whereby the horizontally disposed edge of the added card will cover the exposed margin of the index element and be readily viewed, so that the data contained thereon may be noted.

While I have illustrated and described certain preferred forms of my invention, I do not limit myself to the exact details shown, as many other modifications and variations are possible which will lie within the spirit of the invention and the scope of the appended claims.

25 What I claim is:

1. In an index or file of the class described, an index element having a corner-protecting member secured thereto, said member comprising a plate-like portion adapted to cover a corner of said element, and a pair of arms adapted to engage respectively the edges of said element adjacent the corner thereof and to extend over the opposite surface of said element, said arms terminating beyond said plate-like portion in pointed ends, said ends being adapted to be secured to said index element to retain the corner member in position.
2. In an index or file, a pair of reference members in superimposed relation with the side edges and a marginal edge of one coinciding with the corresponding edges of the

other, and means secured to one adapted to detachably retain the other thereon, said means comprising a pre-formed member 45 having a triangular shaped plate portion provided with a pair of arm members secured to two edges thereof, said arm members extending toward the third side of said plate portion and spaced therefrom, said arm 50 members and plate portion engaging opposite outer faces of said reference members.

3. In an index or file, a pair of reference members in superimposed relation with the side edges and a marginal edge of one coinciding with the corresponding edges of the other, and means secured to one adapted to detachably retain the other thereon, said means comprising a pre-formed member 55 having a plate portion and a pair of arms spaced therefrom, said plate portion and said arms engaged over opposite sides of said reference members, and connecting portions between said arms and plate portion beyond adjacent edges of said reference members. 60 65

4. A reference member for an index or file, having card-holding means secured thereon whereby said reference member is capable of detachably supporting a card, said means comprising a pre-formed member 70 having a triangular plate portion positioned in coincident relation with a corner of said reference member and spaced therefrom to form a card-receiving pocket, and a pair of arms extending from two edges of said plate 75 portion beyond the side and marginal edges of said reference member and into spaced parallel relation with the plate portion and secured to the back of the reference member for retaining said plate portion in spaced 80 relation to the front thereof.

In witness whereof, I have hereunto set my hand this 26th day of June, 1925.

WILLIAM H. DAY.
